US00D786734S

(12) United States Design Patent (10) Patent No.: US D786,734 S
Weiser et al. (45) Date of Patent: * May 16, 2017

(54) FLAMINGO NOVELTY

(71) Applicant: Exhart Environmental Systems, Inc.,
Chatsworth, CA (US)

(72) Inventors: Michael Weiser, Calabasas, CA (US);
Margaret Weiser, Tarzana, CA (US)

(73) Assignee: Exhart Environmental Systems, Inc.,
Chatsworth, CA (US)

() Term: 15 Years

(21) Appl. No.: 29/559,853

(22) Filed: Mar. 31, 2016

(51) LOC (10) Cl. 11-02

(52) U.S. Cl.

USPC D11/162; D21/458; D21/606

(57) CLAIM

The ornamental design for a flamingo novelty, as shown and described.

DESCRIPTION

FIG. 1 is a perspective view of our flamingo novelty;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown illustrate portions of the flamingo novelty that form no part of the claimed design.

1 Claim, 5 Drawing Sheets
